FIG. 1

FIG. 2

FIG. 1 is a right side, top and front perspective view of a combined record player and amplifier, showing our new design; and

FIG. 2 is a left side, top and front perspective view, with a transparent dust cover affixed thereto.

The rear of the record player and amplifier is plain and unornamented.

Portions of the figures are shaded to indicate contrast and appearance, and portions are diagonally lined to indicate transparency.

The structure which would be visible through the transparent cover of FIG. 2 has been omitted for convenience in illustration.

We claim:

The ornamental design for a combined record player and amplifier, as shown and described.
